UNITED STATES PATENT OFFICE

148,513

DESIGN FOR AN EARRING OR SIMILAR ARTICLE

Henry Zweig, Brooklyn, N. Y.

Application October 26, 1946, Serial No. 134,269

Term of patent 3½ years

(Cl. D45—9)

To all whom it may concern:

Be it known that I, Henry Zweig, a citizen of the United States of America and a resident of Brooklyn, in the county of Kings and State of New York, have invented a new, original, and ornamental Design for an Earring or Similar Article, of which the following is a specification, reference being had to the accompanying drawing, forming part thereof, in which—

Fig. 1 is a front view of an earring embodying my design; and

Fig. 2 is a side view thereof.

I claim:

The ornamental design for an earring or similar article, as shown.

HENRY ZWEIG.
